CLAIM

The ornamental design for a removable item carrier for strollers, as shown and described.

DESCRIPTION

FIG. 1 is a top perspective view of a removable item carrier for strollers showing our new design;

FIG. 2 is a rear elevation view thereof.

FIG. 3 is a right side elevation view thereof; the left side being a mirror image thereof.

FIG. 4 is a bottom view thereof.

FIG. 1

FIG. 4

FIG. 2

FIG. 3
